UNITED STATES PATENT OFFICE.

ALFRED K. SIMMONS, OF FARIBAULT, MINNESOTA, ASSIGNOR OF THIRTY-FIVE ONE-HUNDREDTHS TO GUS N. BOOSALIS AND FIFTEEN ONE-HUNDREDTHS TO LUCIUS A. SMITH, BOTH OF FARIBAULT, MINNESOTA.

ARTIFICIAL TOOTH OR CROWN AND FASTENING MEANS THEREFOR.

Application filed August 24, 1922. Serial No. 584,115.

This invention relates to new and useful improvements in artificial teeth or crowns and fastening means therefor.

This invention is particularly adapted to effect the replacement of extracted or decayed teeth that cannot be filled. For this purpose there are provided tooth bodies or crowns shaped to simulate various human teeth and preferably these artificial teeth are formed of porcelain. The means of securing such teeth in place is by way of a post and interlocking attachment made of metals commonly used in dentistry. Among the advantages residing in the employment of this novel tooth and fastening are the use of less metal and more porcelain; the use of a solidly constructed porcelain tooth instead of a thinly constructed tooth; the occlusal surfaces of the teeth may be of porcelain instead of gold in incisors, canines, bicuspids and molar teeth. Further the tooth may be accurately adapted to the root by grinding to effect an accurate union between the root of the tooth and the artificial body or crown; and, as the tooth is cemented to the post or pin, there is afforded an interchangeability and replaceability.

The object, therefore, of this invention is to provide an improved artificial tooth or crown and fastening means therefor.

Other objects of the invention will more fully appear from the following description and the accompanying drawings, and will be pointed out in the annexed claims.

In the accompanying drawings there has been disclosed a structure designed to carry out the objects of the invention but it is to be understood that the invention is not confined to the exact features shown as various changes may be made within the scope of the claims which follow.

In the drawings:

Figure 1 is a view in front elevation of the novel post or pin;

Figure 2 is a vertical sectional view through the post shown in Figure 1 with a porcelain tooth or crown cemented thereto;

Figure 3 is a cross-sectional view on the line 3-3 of Figure 1;

Figure 4 is a plan view of a tooth or crown to show the recess provided in the tooth shown in Figure 2.

It is old in this art to implant posts in apertures drilled into the roots of natural

teeth, and it is also old in this art to secure 55 artificial teeth or crowns to such implanted posts. This invention more particularly resides in the fastening means whereby the artificial teeth or a crown is held in position, which fastening means includes the 60 novel post as shown.

The novel form of post here shown is preferably of a suitable metal and is upwardly tapered in order to facilitate introduction of the post into the drilled root. 65 The post is provided with a longitudinally extending channel 17 within which the cement is received when the post is implanted in the root. The provision of this longitudinally extending channel and the reception 70 of the cement therein successfully prevents subsequent rotation of the post about its longitudinal axis. Such post rotation is disadvantageous in that the occlusal surface of the tooth is moved out of proper position. 75 Furthermore, the post is provided with a plurality of shoulders 18 toward the outer end of the post. Such shoulders are conveniently formed by successively cutting away portions of the post to provide individual tapered sections, each terminating in a shoulder. In the form shown in Figures 1 to 3 inclusive the outer end of the post has an integral collar 19. In the form there shown such collar is square and preferably 80 two of its edges are provided with grooves 85 21. Each such groove 21 extends from a portion of one face along the angled junction with the other face and a short distance along such adjacent face. The outer 90 end of the post terminates in a block 22. The form of this block is more particularly shown in the cross-sectional view, Figure 2, wherein the block 22 is shown outwardly tapered on two sides and is terminally provided with two opposed V-shaped abutments 95 23 and 24. The abutment 23 is preferably formed longer than the opposed abutment 24.

A tooth or crown which is adapted to be used with this novel post is provided with a recess suitably shaped to receive the post collar 19 and the abutments 23 and 24 therein. In Figure 2 there is shown such cemented assembly of post and crown. The base portion of the crown shown in Figure 4 is 100 provided with a recess complementary to the post heretofore described. This crown 25 has an inwardly presented square recess 105 26

adapted to receive the correspondingly shaped collar 19 of the post while the median portion of the recess 26 is countersunk to provide the two V-shaped recesses 27 and 28. Recess 27 is deeper and is adapted to receive the longer abutment 23 of the post, while the recess 28 receives the relatively shorter abutment 24. While these recesses 27 and 28 in the base portion of the crown 10 are symmetrical with respect to the outer end of the post they are slightly larger than the two abutments in order to receive the cement 29 whereby the crown is held on the post.

15 I claim as my invention:

1. The combination of a dental post having a longitudinal channel and a plurality of transverse corrugations, said post being adapted to be cemented in a recess, a collar 20 on said post adjacent its outer end and adapted to be cemented within a suitably shaped socket in a crown or similar article,

a groove in the edge of the collar whereby cement may be received therein and the collar retentively held, and terminal abutments 25 on said post adapted to be received and cemented within a socket in said crown.

2. The combination of a dental post having a longitudinal channel and a plurality of transverse corrugations, said post being 30 adapted to be cemented in a recess, a collar on said post adjacent its outer end and adapted to be cemented within a suitably shaped socket in a crown or similar article, a groove in the edge of the collar whereby cement may be received therein and the collar retentively held, a depending substantially 35 V-shaped abutment on said post adapted to be received and cemented within a suitably shaped socket in said crown or 40 similar article.

In witness whereof, I have hereunto set my hand this first day of August 1922.

ALFRED K. SIMMONS.
